DESIGN FOR A GRINDING WHEEL UNIT

Milburn A. Hollengreen and Ralph E. Price,
Waynesboro, Pa., assignors to Landis Tool
Company, Waynesboro, Pa.

Application March 29, 1940, Serial No. 91,343

Term of patent 14 years

To all whom it may concern:

Be it known that we, Milburn A. Hollengreen and Ralph E. Price, citizens of the United States of America, residing at Waynesboro, in the county of Franklin and State of Pennsylvania, have invented a new, original, and ornamental Design for a Grinding Wheel Unit, of which the following is a specification, reference being had to the accompanying drawing, forming part thereof.

Figure 1 is a front perspective view of a grinding wheel unit showing our new design; and

Figure 2 is a rear perspective view thereof.
The essential feature of our design resides in the portions indicated in full lines.

We claim:
The ornamental design for a grinding wheel unit, substantially as shown and described.

MILBURN A. HOLLENGREEN.
RALPH E. PRICE.
